TWO-STEP PRESSING MACHINE

Ernest Davis, Syracuse, N. Y., assignor to The Prosperity Company, Inc., Syracuse, N. Y., a corporation of New York

Application April 25, 1929, Serial No. 358,141
Renewed February 11, 1933

11 Claims. (Cl. 68—9)

This invention relates to pressing machines as garment and laundry platen or ironing presses having an opening and closing movement, and has for its object a press which is provided with 5 a particularly simple motor means and control therefor for preliminarily closing the press and a pedal operated means for finally closing the press under heavy pressure.

The invention consists in the novel features 10 and in the combinations and constructions hereinafter set forth and claimed.

In describing this invention, reference is had 15 to the accompanying drawings in which like characters designate corresponding parts in all the views.

Figure 1 is a side elevation of a machine embodying my invention.

Figure 2 is an enlarged fragmentary rear elevation of parts seen in Figure 1.

Figure 3 is a side elevation, partly broken away, 20 looking to the left in Figure 2.

Figure 4 is a detail fragmentary view of the clutch for controlling the preliminary closing of the press.

Figure 5 is a diagrammatic view showing the 25 circuit of the electric motor.

Operator-operated garment and laundry presses, and particularly presses adapted to work on outer garments, have certain advantages over 30 motor operated presses, both in quality of work and speed of production, but the former are disadvantageous because of the fatigue to the operator.

The advantages are that the operator can hold 35 the work arranged on the buck or stationary jaw until the last second without danger while closing the press with the pedal or with one hand pulling the head or movable jaw closed, as the unconscious mental reaction of the operator is 40 not to fully close the press while one or both hands are between the jaws or in a dangerous position and to intuitively withdraw the hands when the press closes to a dangerous proximity to the hands.

45 The chief cause of fatigue in operator-operated presses is the reaching effort by hand or foot to preliminarily close the press from wide open position to preliminarily closed position. Usually the operator reaches for a handle on the press head with one hand, and then for the pedal with one foot.

Outer garment presses, commonly known as 50 tailor presses are not generally power operated because of the human element required in the

operation, that is, the feeling or sensing of pressure applied to the garment. Some garments requiring very light pressure and other garments requiring heavy pressure for proper pressing. There is also the seaming and stretching or 5 shrinking of the garment into shape. Therefore, the ordinary laundry power press, which merely closes under heavy pressure, is not suitable. The manually operated press is fatiguing to the operator, especially the starting of the 10 press head in motion. The press heads are usually started in motion by pulling down on them. Reaching up for the handle and lifting the foot high to reach the pedal while standing on one foot are extremely fatiguing to the operator. 15 However, if the closing of the press head into light contact with the garment is accomplished by power means, the greater part of the fatigue to the operator is eliminated. Also, if the treadle is used only for applying pressure, the movement of the treadle may be made very short and the pedal located close to the floor. Also, the application and graduation of the pressure to the garment is still applied by and within the control of the operator.

20 The invention is directed to means for eliminating the disadvantageous features of the foot press and at the same time retaining the good features.

25 The pressing machine of my invention comprises, generally, cooperating pressing jaws or elements, one of which is movable toward and from the other, motor means and motion transmitting means or connections operated thereby to preliminarily close the press, a pedal, connections operated thereby to finally close the press under heavy pressure and means, preferably a 30 pedal, to control the motor means. In other words, the machine has a two step operation, 35 first into a preliminarily closed position and second into final pressure position. The first step is effected by operator controlled power means and the second step, by means as a pedal to which force is applied by the operator.

40 The invention is illustrated as embodied in a conventional pressing machine having press jaws comprising a head 1 movable toward and from a buck 2. The buck 2 is carried on a suitable bracket or bolster 3 which is mounted on the machine frame 4. The head 1 is carried at the 45 front end of a yoke or press lever 5 pivoted between its ends at 6 to an upright 7 rising from the frame.

45 The motor for preliminarily closing the press is preferably a relatively small electric motor 8 50

suitably mounted on the frame and the armature shaft 9 thereof is connected to the head 1 through motion transmitting means including a normally open or disengaged clutch. The clutch includes a shiftable section which is shifted into engaged position by an operator-operated member or pedal. The pedal also preferably operates a switch which closes the circuit through the motor.

The fixed and shiftable sections 10 and 11 of the clutch are respectively loosely mounted on and slidably keyed to a shaft 12, that is, the shaft 12 is normally free to rotate in the section 10 but is keyed to the shiftable section 11. A worm gear 13 which meshes with a worm on the armature shaft 9 is carried by the shaft 12. The section 10 has a rock arm 15 which is pivoted at 16 to one end of a link 17, the other end of which link is pivoted at 18 to the rear arm of the yoke lever 5.

20 The motor is preferably, normally idle and is connected in a suitable electric power circuit by a normally open switch 19 which is closed by the operation of an operator actuated means or a pedal 20. The pedal also shifts the clutch section 11 into engaged position. Preferably, a suitable automatically-operated normally closed switch 21 is also connected in the motor circuit.

25 The operator actuated switch 19 and the automatically operated switch 21 comprise control means which is normally in inoperative or disconnected position as determined by one of the switches being open irrespective of whether or not the other switch is closed. Thus, upon opening of the automatically operated switch 21, the control means is in inoperative or disconnected position irrespective of the position of the switch 19. In other words, the control means is in operative position when both switches are closed and is in inoperative position when one switch is open. The mechanism for connecting the motor means 8 with the source of power includes, therefore, the power connection or circuit having the control means, which connection controls the supplying of power to close the press, and the shunt or holding connection or circuit 48 which is connected in parallel with the automatically operated switch 21 and in the particular construction disclosed, controls the supply of power to hold the press closed.

30 The pedal 20 is pivoted at 22 to the base of the machine frame and is connected to the clutch section 11 to shift it into engagement with its cooperating clutch section 10. Suitable connections are provided such as a push rod 23 pivoted to one arm of an angle lever 24, Figure 1, pivoted at 25 to the frame. A link 26 is pivoted to the other arm of the angle lever 24 and at 27 to one arm of a similar angle lever 28 pivoted at 29 to the frame. A link 30 is pivoted at one end at 31 to the other arm of the lever 28 and at its other end at 32 to an arm 33 on a shifting fork 34 pivoted at 35 to the frame, the fork working in a groove in the shiftable clutch section 11. The depression of the pedal 20 is against the action of a suitable returning spring 36.

35 The normally open switch 19 may be of any suitable construction and is operated by the plunger 37 carried by the lever 20, the plunger being capable of yielding, for obvious reasons, against the action of a spring 38 during the depression of the pedal.

40 The normally closed switch 21 is automatically opened, when the head 1 is closed, by a cam or knock off arm 39 rotatable with the clutch section 10 and keyed thereto by a set screw 40. The

arm 39 coacts with the tail 41 of a switch 21. The switch is closed by a spring 42. The two switches 19 and 21 are switch means included in a circuit for applying a high voltage to the motor 8 and controls the operation thereof. Obviously, when 5 one of the switches is open the circuit is open and high pressure electrical energy is cut off from the motor. When the automatic switch 21 is opened, the switch means has been actuated to discontinue the flow of electrical energy through 10 the high voltage circuit to the motor 8.

45 Obviously, depression of the pedal 20 will throw the clutch section 11 into engagement with the section 10 and also close the switch 19 in the motor circuit so that the current at high pressure or voltage is free to pass from feed wire 43 through the switch 19, wire 44 through switch 21, wire 45 to and through the motor, wire 46 back through the switch 19 to feed wire 47. Hence the motor 8 is energized and preliminarily closes 20 the press through the shaft 12, engaged clutch sections 10, 11, the arm 15, link 17 and yoke lever 5. As the head closes, the cam or knock off arm 39 opens the switch 21 so that high pressure power or energy is no longer applied to the 25 motor. However, in order to hold the press in preliminarily closed position as long as the operator holds the pedal depressed and without subjecting the motor to injury or burning out, a resistance 48 is connected in shunt around the 30 switch 21 which applies low pressure power or voltage to the motor. The arrangement of lever- 35 age is such that only a small amount of motor torque is necessary to hold the head down. Thus, when the switch 21 opens, a sufficient amount of current passes through the resistance 48 to the motor to hold the press closed, but the current is insufficient to over-heat or burn out the motor.

40 When the pedal 20 is released, the spring 36 returns the parts, which were operated by the 45 pedal, to their normal position. One such part is the clutch member 11 which disengages from the clutch member 10 thereby permitting the latter and the arm 15 to return to initial position when the press opens. The clutch section 45 10 and cam or knock off arm 39 are returned to their starting position by the opening of the press under the influence of the usual counter-springs 49, 50. The spring 49 has one end connected to the rear arm of the yoke lever 5 and 50 the other end to the frame and the spring 50 has one end connected with the frame and the other end is connected to the actuating mechanism for applying final pressure.

45 A pedal 51 applies final pressure to the head 55 1 after it has been preliminarily closed by the motor 8. The pedal is here shown as carried by the front end of one arm 52 of an angle lever pivoted at its angle at 53 to the frame, the other arm 54 of the angle extending upwardly and being pivoted at its upper end at 55 to the lower end of a link 56, which link is pivoted at 56 to the rear arm of the yoke lever 5. The arm 54 and link 56 form a toggle. The spring 59 is connected at one end to the angle lever arm 52. 65

50 The motor serves to hold the press in preliminarily closed position as long as the pedal 20 is held depressed. The press is held in its final closed position without the operator holding the pedal 51 depressed by a latch 57 which is 70 pivoted at 58 to the angle lever arm 52 and coacts with the latch lock or keeper 59 on the frame. The latch has a forward extension 60 having a pedal 61 which latch and extension are so hung on the pivot 58 that depression of the 75

operating pedal 51 engages the latch and depression of the pedal 61 trips or releases the latch.

In operation, the operator depresses the pedal 20, shifting the clutch section 11 into engaged position and closing the switch 19 in the motor circuit so that the motor is energized and the motion thereof transferred to the head to preliminarily close it or bring it down on the buck 2. The operator then steps on the pedal 51 for any degree of final pressure. If desired, the operator can omit the preliminary closing step by the motor and operate the press as any foot press by using only the pedal 51.

Various modifications will occur to those skilled in the art in the configuration, composition and disposition of the component elements going to make up the invention as a whole as well as in the selective combination or application of the respective elements, and no limitation is intended by the phraseology of the foregoing description or illustrations in the accompanying drawings.

What I claim is:

1. In a pressing machine, cooperating pressing elements, one of which is movable toward and from the other, an electric circuit, a motor operatively connected to the movable element and connected in said circuit, a normally open switch in the motor circuit, an operating member operable to close the switch, a normally closed switch in the motor circuit, a resistance coil connected in shunt in the motor circuit around the normally closed switch, and means actuated by the motor to open the normally closed switch when the press closes.

2. In a pressing machine, cooperating pressing elements, one of which is movable toward and from the other, an electric circuit, a motor operatively connected to the movable element and connected in said circuit, a normally open switch in the motor circuit, an operating member operable to close the switch, a normally closed switch in the motor circuit, a resistance coil connected in shunt in the motor circuit around the normally closed switch, means actuated by the motor to open the normally closed switch when the press closes, and releasable means for locking the press closed.

3. A garment or ironing press comprising cooperating pressing jaws which open and close on the work; operating mechanism to open and close the press including motor means to close the press, motion transmitting means connecting the motor means with the movable jaw, a normally open clutch included in the motion transmitting means, and means to open the press upon release of the clutch; mechanism connecting the motor means with a source of high pressure power including control means normally in inoperative position; operator actuated means for operating the control means to energize the motor means and for engaging the clutch, automatic means operable when the press reaches closed position for controlling the control means so that high pressure power to the motor means is discontinued through the control means; and means for holding the press in closed position.

4. A garment or ironing press comprising, cooperating pressing jaws one of which is movable toward and from the other; operating mechanism to open and close the press including, motor means to close the press, motion transmitting means connecting the motor means with the movable jaw, a normally open clutch included in the motion transmitting means, and means to open the press upon release of the clutch; mechanism

connecting the motor means with a source of power including, control means normally in inoperative position; operator actuated means for operating the control means to energize the motor means and engage the clutch, automatic means operative when the press reaches closed position for controlling the control means so that the high pressure power to the motor to close the press is discontinued, and a connection to the motor means to supply sufficient power to the motor means to hold the press in closed position upon actuation of the automatic means when the press reaches closed position.

5. A garment or ironing press comprising, co-operating pressing jaws one of which is movable toward and from the other; operating mechanism to open and close the press including, an electric motor, motion transmitting means connecting the motor with the movable jaw, a normally open clutch included in the motion transmitting means, and means to open the press upon release of the clutch; a power circuit connected with the motor and adapted to be connected with a source of power including switch means to connect the motor with and to disconnect the same from the high voltage power to close the press; operator actuated means for operating the switch means to energize the motor and engage the clutch, automatic means controlling the switch means when the press reaches closed position to discontinue the application of high voltage electrical energy to the motor through the power circuit to close the press; a holding circuit connected with the motor to feed limited power thereto to hold the press in closed position.

6. A garment or ironing press comprising, co-operating pressing jaws one of which is movable toward and from the other; operating mechanism to open and close the press including, motor means, motion transmitting means connecting the motor means with the movable jaw, a normally open clutch included in the motion transmitting means, and means to open the press upon release of the clutch; a first connection connecting the motor means with a source of power including, control means normally in open position; operator actuated means for operating the control means to energize the motor means and engage the clutch; a second connection connected with the motor means to feed limited energy thereto to hold the press in closed position, and automatic means controlling the connections when the press reaches closed position to discontinue electric energy through the first connection and controlling the flow of energy through the second connection.

7. A garment or ironing press comprising, co-operating pressing jaws one of which is movable toward and from the other; operating mechanism to open and close the press including, an electric motor, motion transmitting means connecting the motor with the movable jaw, a normally open clutch included in the motion transmitting means, and means to open the press upon release of the clutch; a first circuit connecting the motor with a source of power including, switch means normally in open position; operator actuated means for operating the switch means to energize the motor and engage the clutch; a second circuit connected with the motor to feed limited energy thereto to hold the press in closed position; and automatic means controlling the switch means when the press reaches closed position to discontinue electric energy through

the first circuit and controlling the flow of energy through the second circuit.

8. A garment or ironing press comprising, co-operating pressing jaws one of which is movable toward and from the other; operating mechanism to open and close the press including, a rotary electric motor, motion transmitting means connecting the motor with the movable jaw, and means to open the press upon energy being cut off from the motor; mechanism connecting the motor with a source of power including, switch means normally in open position; operator actuated means for operating the switch means to energize the motor; automatic means controlling the switch means when the press reaches closed position to discontinue the power supply to the motor; and a circuit connected with the motor to feed limited power thereto to hold the press in closed position.
9. A garment or ironing press comprising, co-operating pressing jaws one of which is movable toward and from the other; operating mechanism to open and close the press including, a rotary electric motor, motion transmitting means connecting the motor with the movable jaw, a normally open clutch included in the motion transmitting means, and means to open the press upon energy being cut off from the motor; mechanism connecting the motor with a source of power including, a first circuit having switch means normally in open position; operator actuated means for operating the switch means to energize the motor; a second circuit connected with the motor to feed limited power thereto to hold the press in closed position; and automatic means controlling the switch means when the press reaches closed position to discontinue electric energy through the first circuit and control the passage of energy through the second circuit.
10. A garment or ironing press comprising co-operating pressing jaws one of which is movable toward and from the other; operating mechanism to open and close the press including motor means to close the press, motion transmitting means connecting the motor means with the movable

jaw, a normally open clutch included in the motion transmitting means, and means to open the press upon release of the clutch; a high pressure power connection with the motor means for supplying power to close the press and adapted to be connected with a source of power including control means to connect the motor means with and disconnect the same from the source of power; operator actuated means for operating the control means to energize the motor means and for engaging the clutch; automatic means operative when the press reaches closed position for controlling the control means so that the high pressure power for closing the press is discontinued to the motor means through the power connection; and means to hold the press in closed position upon actuation of the automatic means when the press reaches closed position.

11. A garment or ironing press comprising co-operating pressing jaws one of which is movable toward and from the other; operating mechanism to open and close the press including motor means to close the press, motion transmitting means connecting the motor means with the movable jaw, a normally open clutch included in the motion transmitting means, and means to open the press upon release of the clutch; a high pressure power connection with the motor means for supplying power to close the press and adapted to be connected with a source of power including control means to connect the motor means with and disconnect the same from a source of power; operator actuated means for operating the control means to connect the motor means with a source of power and for engaging the clutch; automatic means operative when the press reaches closed position for controlling the control means so that the high pressure power to the motor means for closing the press is discontinued through the power connection; and a holding connection to the motor means to supply sufficient power to the motor means to hold the press in closed position upon actuation of the automatic means when the press reaches closed position.

ERNEST DAVIS. 45
